UNITED STATES PATENT OFFICE

BLAINE H. HARRIS AND EARL F. CRAFT, OF ST. PAUL, MINNESOTA, ASSIGNEES TO
BROWN & BIGELOW, OF ST. PAUL, MINNESOTA, A CORPORATION OF MINNESOTA

ASH RECEIVER

Application filed March 5, 1929. Serial No. 344,350.

Our invention relates to an ash receiver wherein a non-tipping type of ash receiver is designed of a particular nature having a construction wherein the body portion is formed virtually vertical with a suitable weighted base portion and a closure for the top which forms the ash receiving space, and which is removable easily for cleaning the ash receiver.

10 A feature of the invention resides in an ash receiver wherein the ash tray is formed as a cover for the ash receiver, adapted to hinge in a manner so that the cover is built to discharge the ashes in the ash tray cover into 15 the ash receiver. The tray cover is virtually semi-spherical in shape, thus providing a deep receiver for ashes when the ash receiver proper is closed by the tray cover. Suitable rests are formed projecting from the edges 20 of the ash tray cover, so that a cigarette or cigar can be rested upon the same when it is desired.

25 A further feature of the invention resides in the particular removable means of attaching the ash tray receiver to the open top of the ash receiver body. The ash tray cover is formed flexible so that it can be pinched inwardly on the sides, and the lugs which are formed integral with the side of the same 30 that forms the pivot point for the tray cover are thus released from the recesses which hold them ordinarily in place to hinge the cover, and the ash tray cover is thereby easily removed so that the entire contents of the receiver may be readily cleaned out.

35 The invention includes an ash receiver of a spherical nature which will not tip over, and having a cover which closes the ash receiving chamber of the receiver sufficiently tight to snuff out a lighted cigar or cigarette which is placed in the body of the ash receiver. This is an important feature, yet providing a removable cover, and one which may be turned over to discharge the ashes from the cover into the body.

40 These features, together with other features and objects of the invention will be more fully and clearly set forth hereinafter 45 in the specification and claims.

In the drawing forming a part of this specification,

Figure 1 is a perspective view of our ash receiver.

Figure 2 is a side sectional view of the same 50 showing the cover in dotted outline, to show the operation of discharging the ashes from the tray cover into the body of the receiver.

Figure 3 illustrates a plan view of the cover removed from the ash receiver. 55

In the drawing our ash receiver A is formed with a body portion virtually cylindrical in shape so as to provide an upper portion 10 and lower portion 11. The upper portion 10 is formed with an inturned flange 12 about 60 the opening 13, and the opening 13 is quite large so as to receive a cover member 14.

The cover member 14 is formed virtually semi-cylindrical which thus forms a very deep ash receiving tray and projecting from the 70 cover 14 are two rests 15 which may be formed integral with the cover and which project angularly from the same in a manner so that one or more cigarettes or cigars may be laid on the tray with the ash end pointing toward 75 or over the ash receiving tray cover 14.

The cover 14 is formed with pivoting lugs 16 which project from either side of the same, and which are adapted to engage in the openings 17 of the eyelet ears 18. The eyelet 80 ears 18 are formed projecting upward from the edge of the opening 13.

The ash receiving tray cover may be easily removed from its pivot attachment to the ash receiver A by pinching the sides of the tray 85 14 together sufficiently to release the lugs 16 from the ears 18 of the upper member 10.

The lower portion of the ash receiver A is semi-cylindrical in formation and is provided with a weighted base member 20 which is 90 formed with an integral riveting member 21 and thus is riveted to the base in a manner so that it will hold the weighted member 20 in the bottom, and thus forms a means of balancing the receiver A to prevent it from 95 tipping over when in use and thus discharging the ashes out of the same.

We have found our ash receiver to be of a very desirable nature owing to its extreme simplicity, being formed from three major 100

parts, the upper portion 10, the lower portion 11 and the cover 14. These parts, together with the weighted member 20, form the entire ash receiver, and in this manner we 5 provide a very simple, inexpensive structure, yet forming an ash receiver which is provided with a closure which is adapted to snuff out any lighted cigarettes when placed within the receiver. The tray cover shuts off the 10 air sufficiently so that the lighted cigarette will go out without smoking from the receiver into the outer atmosphere.

The quick and easy removal of the cover provides an ash receiver which can be readily 15 cleansed, and also provides an ash receiving cover which can be easily turned over to dump the contents of the receiver cover or tray into the body of the ash receiver, yet virtually closing the opening of the ash receiver when 20 the cover is either in turned over position or in position to have its hole portion formed by its semi-cylindrical nature extending into the body or inner chamber of the ash receiver A. 25 Our ash receiver forms a utility for forming in a very neat and tidy manner an ash receiving article which accomplishes the results, and also an attractive utility.

In accordance with the patent statutes we 30 have described the principles of operation of our ash receiver, together with the best embodiment thereof, and desire to have it understood that the drawing is only suggestive and that the invention may be carried 35 out by other means apart from those illustrated within the scope of the following claims.

We claim:

1. An ash receiver comprising a semi- 40 spherical base portion, a weighted member in said base portion, a frusto-spherical upper portion having a large opening in the top thereof, eyelet ears formed in the edges of said opening, and a flexible ash receiver cover tray 45 pivotally and removably secured in said opening.

2. An ash receiver, including a non-tipping body portion formed substantially spherical, a resting surface formed in said body portion, an opening formed in the top of said body portion, having a collar projecting about the same, ears projecting upwardly from said collar, flexible ash-receiving tray pivotally and removably secured to said ear 55 by pinching together said tray, said tray being positioned in a manner to permit the discharge of the contents thereof into the body of the receiver by rotating said tray, and rests projecting from said ash receiver tray 60 for supporting smoker's articles.

3. A non-tipping ash tray, including a body portion, substantially spherical, a weighted member secured within the bottom thereof, a large opening formed in the top and a flexible ash-receiving cover tray, having a pair 65

of adjacent radially disposed rests projecting therefrom and means for pivotally supporting said tray.
